VOTING MACHINE

Alvin N. Gustavson, Bemus Point, N. Y., assignor
to Automatic Voting Machine Corporation,
Jamestown, N. Y., a corporation of Delaware

Application December 19, 1942, Serial No. 469,540

9 Claims. (Cl. 20—3)

This invention relates to an improvement in voting machines and more particularly to a mechanism for controlling a curtain actuator therefor.

In its presented form, the invention is applied to a voting machine curtain operating mechanism of the general type disclosed in the A. N. Gustavson Patent No. 2,284,144, dated May 26, 1942. The invention is particularly adapted to requiring complete movement of a curtain or other enclosure in one direction of travel before movement can be effected in the opposite direction.

In some instances it has been found that a voter has, through the connivance or neglect of an election official, been able to cast more than the single ballot to which he is entitled and without others being aware of it. As is well known, a voter on entering the booth of a voting machine, operates a lever or button that moves a curtain or enclosure into closed position, this lever being released for such operation by the machine attendant through manipulation of a control or entrance knob. When a voter has completed his ballot, he is normally expected to actuate the same lever which will, subsequent to actuating registering and indicator return mechanism, open the curtain. If, however, prior to such manipulation, the voter grasps the curtain or the cord by which it is moved, or some other movable connection, he may hold it in closed position, thus unlocking the machine for the casting of a further ballot. Of course the entrance knob during such procedure must be in a position to release the curtain lever.

To prevent such practise, the present invention requires the mechanism by which the curtain is moved into opened position to have been fully actuated and in the present disclosure of a curtain actuating mechanism such mechanism will not complete its cycle if the curtain is held or otherwise prevented from moving into fully open position. Under such circumstances, a locking mechanism operates to prevent actuation of the curtain lever in a manner that would normally again close the curtain.

The invention has for one of its more particular objects the provision of a mechanism by which to prevent operation of a curtain actuating mechanism, if such mechanism has in any way been prevented from functioning in a prescribed manner.

Another object of the invention lies in the provision of a device for manual or motor driven curtain actuating mechanisms which will prevent

continued operation if the cycle of operation is interfered with.

Another and more specific object of the invention lies in the provision of a means for locking a curtain actuating lever in a given position when the curtain actuating mechanism has been unable to move the curtains into a prescribed position.

Other objects and advantages will be more fully understood from a consideration of the following specification taken in conjunction with the accompanying drawings, and in which

Figure 1 is a fragmentary prospective view of the upper front portion of a voting machine, in which is embodied one form of the invention;

Figure 2 is an enlarged plan view of the curtain actuating mechanism mounted in the upper part of a voting machine, the position of the parts corresponding to open position of the curtains, being taken substantially on the line 2—2 of Figure 3;

Figure 3 is a front elevational view of the curtain actuating mechanism, operating lever, and lever control, the parts being in curtain open position;

Figure 4 is a view similar to Figure 3, showing the position of the parts in curtain closed position;

Figure 5 is a fragmentary elevational view of the control mechanism showing extent of movement from solid line latched position to dotted line unlatched position; and

Figure 6 is a fragmentary elevational view of a part of the curtain actuating mechanism when in curtain closed position.

Figure 7 is a plan view of the curtain actuating mechanism with the parts in the position indicated in Fig. 8;

Figure 8 is a fragmentary elevational view of a part of the curtain actuating mechanism, showing the operating lever stopped after initial movement by the lever control.

Reference is now had to the drawings wherein the numeral 10 is employed to generally designate a voting machine in which one modification of the invention is embodied. The voting machine comprises a cabinet 11, having a voting keyboard 12 on the front wall thereof. Secured to the upper front corners of the cabinet is a U-shaped rod 13 from which is suspended a pair of curtains 14, the curtains being by-parting and when closed assuming substantially the position shown in Figure 1 of the drawings and serving to cooperate with the doors 15 to form an enclosure for a voter.

Mounted in the cabinet 11, directly beneath a top plate 16, is a curtain operating mechanism. This mechanism is carried by a support 17 which in turn is fitted with a downwardly directed shaft 18 on which is mounted a gear 19. Also mounted on the shaft 18 is a flanged pulley 21, the pulley and gear being integral or joined to rotate as one element about the shaft 18. A pin or shaft 22 is carried by the support 17 and pivotally mounts a cam plate 23. This plate is so mounted as to lie within the flanged rim of the pulley 21 and is normally urged into engagement therewith by means of a tension spring 24, one end of which is joined to the support 17 and the other to a pin 25 mounted on a portion of the cam plate 23 remote from its pivotal support 22. The pin 25 also serves as a contact lug for another part of the mechanism hereinafter described. A further shaft 26 carried by the support 17 pivotally mounts a gear segment 27, the teeth 28 of which mesh with the teeth of the gear 19. Gear segment 27 has an offset arm 29 at the end of which two pins 31 and 32 are mounted.

A slideable plate 33 is formed at one end with a slot 34. A stud 36 carried by the top plate 16, projects through slot 34 and supports one end of the plate 33. The other end 37 of this plate is formed with a slot 39 through which pin 32 of the gear arm 29 projects. Pins 32 and 36 support plate 33 for reciprocal movement limited by the length of slots 34 and 39.

A bracket 41, secured to the side wall of the cabinet 11, supports a pin 42 that in turn pivotally mounts a bell crank 43. This bell crank at one end is pivotally joined to one end of a strap 44. The other end of this strap has pivotal connection with a bracket 46 that is secured to the under face of plate 33 adjacent the inner end of slot 34. Approximately midway of the ends of the strap 44 is a pin 47 to which one end of an expansion spring 48 is secured. The other end of this spring is secured to pin 31 of the gear segment arm 29. The other arm of the bell crank 43 is pivotally joined to one end of a link 49. The other end of this link has pivotal connection with a bracket 51 adjacent the end of a vertically disposed bar 52. This bar extends downwardly along the side wall of the cabinet 11, being mounted in suitable guides for reciprocation.

It will be noted that a double pulley block 53 is located adjacent the top wall 16 of the cabinet. At corresponding ends of rod 13, further pulleys 54 and 56 are located. An endless cord or belt 57 is provided which, having several turns about the pulley 21, passes through block 53 and 56, around pulley 54 and back through blocks 56 and 53 to pulley 21. The cord adjacent the front of the machine is thus doubled and the free ends of the curtain 14 are clamped or otherwise joined thereto. Rotation of the pulley 21 in a clock-wise direction causes the cord 57 to travel in the direction of the arrows of Figure 2 for the purpose of moving the curtains from opened to closed position (see Figure 1).

Referring more particularly to Figures 3 and 4, there is shown a structure for actuating the above described curtain operating mechanism. In the present disclosure, beneath the keyboard 12, is a forwardly offset compartment 58 in which is mounted a curtain lever and parts incident thereto. In this compartment is a supporting frame which includes front and rear spaced apart plates. These plates support a

horizontally disposed shaft 63. An operating lever 64 terminates in one end in a handle 66 and at the other end in forks 67, the spacing of the forks being approximately the diameter of the shaft 63. Mounted on the shaft 63 is a hollow rectangular member 69, that includes a collar 71 pinned or otherwise secured to the shaft. A rectangular opening extends lengthwise of the member 69 to facilitate entry of the forked end of the lever 64. Between the spaced apart plates is a disk 72. This disk is mounted on shaft 63 and is caused to rotate with the lever 64. An arm 73, link 74, bell crank 76, further link 77 and bracket 78 serve to operably connect the disk 72 with the lower end of bar 52. Another arm 79, together with link 81, form a part of the connecting means between disk 72 and the voting machine entrance knob.

Also included in the structure for actuating the curtain mechanism is means by which the lever 64 is required to move through its full distance of travel in one direction before it can be moved in the opposite direction. This structure includes a Y-shaped member 94, springs 96, T-shaped member 98, ratchet plate 101, having teeth engageable with the teeth 106 of a gear segment formed on the disk 72.

The lever 64 and associated parts, together with the connections of the curtain operating mechanism and the entrance knob are identical with and bear the same reference numerals as the corresponding parts of the Gustavson Patent No. 2,284,144, referred to above, and for this reason this structure has not been described in detail. In the operation of the voting machine curtain, it is required that the curtain fully enclose a voter prior to the machine being unlocked for casting a ballot. Also following casting a ballot, it is required that such ballot be registered and the indicators or pointers returned to inoperative position before the curtain moves to open position, uncovers the indicators and allows the voter to leave the machine. Thus it is necessary that the curtain operating mechanism be provided with means for direct response during the curtain closing operation and delayed response during curtain opening operation.

Parts by which this curtain response is obtainable include a jointed strap 107, the end 108 of which is slotted to receive a pin 109 carried by the plate 17. Adjacent the end 108, strap 107 is provided with a laterally directed finger 111. This finger is in a plane such that upon lengthwise movement of the strap to the extent permitted by the slot through which pin 109 projected, said arm will contact pin 25 and rotate plate 23. Such rotation of the plate causes it to disengage the rim of the pulley 21 against tension of the spring 24. Adjacent the joint of the strap 107 is an arm 112 which is so directed as to lie in the path of pin 32, being movable by said pin under circumstances hereinafter set out. The other end of the strap 107 is pivotally joined to one arm of a bell crank 113. The other arm of this bell crank has suitable connections with one arm of a further bell crank 116. The other arm of bell crank 116 has pivotal connection with one end of a bar 117. The other end of the bar 117 is in turn pivotally jointed to one arm of a still further bell crank 118. The other arm of this bell crank is fitted with a pin or lug 119. This pin, under certain conditions of operation of the mechanism hereinafter described, is contacted by link

74, and bell crank and associated parts to and including arm 112 are moved from the position of Fig. 4 to that of Fig. 3. It is pointed out that one end of bar 114 together with bell cranks 116 and 118 and bar 117 are all located within the compartment 58.

Also located in the compartment 58 is a latch member 121. This member is mounted upon a pivot pin 122 which is located sufficiently remote from the center of the member to provide definite unbalance thereof. The short end 123 of this member including an upstanding flange 124 which is in the same vertical plane as lug 119. This end of the member also includes an arm 126 that is in the same vertical plane as a pin 127, located near the periphery of the disk 72.

For a full understanding of the structure, a complete voting cycle is set forth as follows. A voter enters the open booth formed jointly by the by-parting curtains 14 and the face of the voting machine. An election official operates the entrance knob which, as disclosed in the aforementioned patent, disengages bar 89 from the disk 72 (compare Figures 3 and 4). Such movement of bar 89 permits movement of the lever 64 from the position of Figure 3 to that of Figure 4. This lever is movable only to the extent determined by stops 105 and in the present showing moves from left to right in a clockwise direction as viewed by the drawing. Movement of this lever causes the linkage heretofore described to move plate 33 and, by reason of pin 32 being engaged with this plate, gear segment 27 is rotated and in turn causes rotation of gear 19 and pulley 21. Rotation of pulley 21, changes the position of the cord or cable 57 to the extent that the curtains 14 connected therewith are moved to fully closed position before the lever 64 has reached the right hand stop 105.

Upon start of movement of the lever 64, in the direction described, pin 31 moves in a direction to be out of contact with arm 112. However, this arm together with jointed strap 107 and connected parts to and including bell crank 118 also move from the position of Figure 3 to that of Figure 4 due to action of a spring 120. Of course the strap 107 has limited travel but such travel is sufficient to disengage finger 111 from the cam plate 23 (see Figure 6). Also bell crank 118, having rotated to disengage lug 119 from flange 124, the latch member 121 is free to pivot by gravity from the position of Figure 3 to that of Figure 4, a suitable adjustable stop 125 determining the limit of movement of said latch member, which limit brings arm 126 into the path of travel of the pin 127 of the disk 72.

It is assumed that the voter has indicated his ballot and desires to leave the booth. The lever 64 is moved from right to left and the linkage connecting this lever with plate 33 functions as already described only in a reverse direction. Return movement of the plate 33, however, does not actuate gear segment 27 until pin 32 is engaged by the opposite end of slot 39. During this movement of plate 33, spring 48 has been extended and gear segment 27 is held against rotation by action of the cam plate 23. Further movement of the plate 33 is obtained by completing movement of the lever 64, that is, into abutment with the stop 105. This final movement of plate 33 causes pin 31 to contact arm 112, moving strap 107 in a direction to cause arm 111 to engage pin 25 and release cam plate 23 from engagement with pulley 21. Thus the en-

ergy of spring 48 may now be readily and quickly transmitted through gear segment 27 and pulley 21, to move the cable 57 in a direction contrary to the arrows for the purpose of opening the curtains.

During movement of strap 107 in a direction to release cam plate 23, said strap has also through bars 114, 117 and bell crank 116 rotated bell crank 118 in a direction to cause lug 119 thereon to rotate latch member 123 and withdraw arm 126 from the path of pin 127. Of course during rotation of disk 72 and because arm 126 has been in raised position, pin 127 has contacted and momentarily rotated the latch member. However, since this latch member up to this point has not been held down by bell crank 118, contact of pin 127 therewith merely depresses this latch to the extent of allowing the pin to move just past arm 126.

The above description of the operation of the parts has been on the assumption that a voter has followed the correct procedure in entering the booth, casting his ballot and opening the curtains. If a voter, however, should attempt to hold the curtain in closed position during his movement of the lever 64 from curtain closed to curtain opened position, he could return the lever 64 to curtain opened position, that is, from the position of Fig. 4 to that of Fig. 3, and such operation of this lever would return plate 33 to the position of Fig. 2. During this movement of the lever 64, stop 107 remains in the position of Fig. 6, and thus cam 23 does not release the pulley for rotation under tension of the now extended spring 48. As the lever 64 nears the stop 105, that is, moving from curtain closed to curtain opened position, link 74 moves downwardly, contacting pin 119 and rotating bell crank 118, together with the associated linkage to and including strap 107. In other words, the last bit of travel of lever 64 serves, through link 74, to release the cam 23 when the mechanism is not able to properly operate by movement of pin 31 into contact with arm 112. Keeping in mind that the curtains are held in closed position by the voter, the bell crank 118 has been moved to tilt the latch member 121 out of the path of pin 127 and thus the parts of the entire structure, with the curtains closed, are in the position shown in Figs. 2 and 3, with the exception that the gear segment 27 remains in its other extreme position. Now, should a voter, through the connivance of an election official who controls the entrance or voting lever release knob, attempt to move lever 64 again into curtain closed position, the initial movement of this lever away from stop 105 allows latch member 121 to tilt upwardly to the position of Fig. 5 into contact with pin 127. Although the lever 64 may have started toward curtain closed position, it can go no further until the voter has released his hold of the curtain or curtain control cables and allowed the pulley and gear segment to return to the position of Fig. 2. However, upon such actuation of these parts, due to spring 48, the curtains will open, and it will be apparent to the public, as well as other election officials, should the voter, through the connivance of any one official, attempt to close the curtains and vote a second time. It will of course be understood that the given voter, upon releasing his hold of the curtain cable and allowing the curtains to open, has finally permitted the normal functioning of the entire mechanism and thus, when another voter enters the booth, and the

election official raises the entrance knob, said other voter may enclose himself by moving the lever 64 from the position of Fig. 3 to that of Fig. 4.

From the foregoing it is evident that the herein described control for a curtain actuator serves to prevent operation thereof in an illegal manner and in the event any part of the curtain operating mechanism or actuator therefor fails for any reason such failure will immediately become apparent by a voter's inability to move the curtains. Although applicant has shown and described only one form of the invention as applied to a specific curtain operating mechanism, it will be understood that the structure may be modified for application to other operators and that such modifications are contemplated as being within the spirit and scope of the invention as defined in the annexed claims.

Having thus set forth my invention what I claim as new and for which I desire protection by Letters Patent is:

1. In a voting machine having a reciprocable mechanism connected with and adapted to operate a curtain, an actuator operably connected with said mechanism, said actuator being operable to repeatedly reciprocate said mechanism, latch means for securing said actuator against repeated operation when said mechanism has failed to complete a given reciprocation, and means operably connecting said latch means with said mechanism, said latch means being operable, by the completion of said given reciprocation of said mechanism, to release said actuator for further operation.

2. In a voting machine having a reciprocable mechanism connected with and adapted to operate a curtain, an actuator operably connected with said mechanism, said actuator being operable to repeatedly reciprocate said mechanism, a latch member movable to an operated position to secure said actuator against further operation when said mechanism has failed to complete a given reciprocation, linkage connecting said latch member with said mechanism, said latch member being moved by complete reciprocation of said mechanism to an inoperative position with respect to said actuator.

3. In a voting machine having a curtain for enclosing a voter, a mechanism connected with and operable to move said curtain into either of two positions, means for actuating said mechanism, further means operable to secure the actuating means against a repeated operation, said further means having operative connection with said mechanism, said mechanism, in response to the actuating means, operating said further means to release and permit further functioning of the actuating means.

4. In a voting machine having a curtain for enclosing a voter, a mechanism connected with and operable to move said curtain into either of two positions, reciprocable means for actuating said curtain mechanism, latch means for said reciprocable means, said latch means normally assuming a position to prevent repeated operation of said reciprocable means, linkage operably connecting said latch means with said mechanism, said mechanism, when actuated by said reciprocable means to move said curtain into one

of said positions, operating said latch means to release and permit further functioning of said reciprocable means.

5. In a voting machine having a reciprocable mechanism connected with and adapted to operate a curtain, an actuator operably connected with said mechanism, latch means movable to render said mechanism inoperative, means connecting said latch means with said mechanism, said mechanism, when actuated by movement of said actuator in one direction, effecting movement of said latch means to release said actuator.

15 6. In a voting machine having a curtain for enclosing a voter and a mechanism operable to move said curtain into open or closed position, an actuator operably connected with said mechanism, means providing successive delayed and direct response of said mechanism to operation of said actuator, latch means operable to secure said actuator against movement effective on said mechanism following movement of said actuator in a direction to give delayed response of said mechanism, and means operable on said latch means to release said actuator, said means being actuated by movement of said actuator in its direction of delayed response.

25 7. In a voting machine having a reciprocable mechanism, an actuator operably connected with said mechanism, means providing successive delayed and direct response of said mechanism to operation of said actuator, a latch member for said actuator, said member, in one position, securing said actuator against operation in a manner to effect direct response of said mechanism, and means operable, by the delayed movement of said mechanism, to move said member into a position to release said actuator to effect direct response of said mechanism.

30 8. In a voting machine having a reciprocable mechanism, an actuator operably connected with said mechanism, means providing successive delayed and direct response of said mechanism to operation of said actuator, a latch member normally occupying a position to engage and secure 35 said actuator against operation in a direction to effect direct response of said mechanism, and means connected with said mechanism operable to move said latch member to disengage said actuator, said last means being operable following a complete operation of said mechanism in the direction of its delayed response.

35 9. In a voting machine having a curtain for enclosing a voter, a mechanism connected with and operable to move said curtain into open or closed position, an actuator for said mechanism, means connecting said actuator with said mechanism in a manner to provide direct response in a direction to close the curtain and delayed response in a direction to open the curtain, a latch member normally occupying a position to engage and secure said actuator against operation in a manner to close the curtain before said mechanism has functioned to open the curtain, linkage connected with said mechanism and operable 45 thereby, during operation of said mechanism to open the curtain, to engage and adjust said latch member into a position to release said actuator for operation in a manner to close the curtain.
